FREQUENCY-MODULATED CARRIER-SIGNAL TRANSLATING SYSTEM

Robert L. Freeman, Flushing, N. Y., assignor to
Hazeltine Corporation, a corporation of Delaware

Application March 1, 1940, Serial No. 321,610

13 Claims. (Cl. 250—20)

This invention relates generally to frequency-modulated carrier-signal translating systems and particularly to systems of such type including signal-translating channels wherein at least one of the characteristics of a frequency-modulated carrier-signal wave is altered for radiation or reproduction.

In the transmission and reception of frequency-modulated carrier signals, it is sometimes desirable to alter at least one of the characteristics thereof before radiation or after reception. For example, in a frequency-modulated carrier-signal transmitter operating according to present practice, a frequency-modulated carrier signal having a small frequency deviation is first generated and then the frequency deviation of the frequency-modulated carrier signal is increased before radiation; while in a frequency-modulated carrier-signal receiver, it is often desirable to convert the received frequency-modulated carrier signal to one having a different type of modulation, for example, amplitude modulation, that is substantially entirely free of frequency-modulation components. Further, in the reception of frequency-modulated carrier signals, it is desirable to effect such conversion as early as possible in the carrier-signal translating channel to avoid the use of wide band selectors which are necessary in conventional frequency-modulated carrier-signal receivers to accommodate the relatively wide frequency-modulation sidebands. Thus, narrow band selectors having a high impedance and consequently a greater gain when included in intermediate-frequency amplifiers may be used in the signal-translating channel after the frequency-modulated carrier signal has been converted to an amplitude-modulated carrier signal, the selectivity being provided primarily by the converter itself or by one or more stages of the signal-translating channel prior thereto.

Furthermore, in the usual type of frequency-modulated carrier-signal receiver, it is customary to convert the frequency-modulated signal to an amplitude-modulated signal before detection, since conventional signal detectors respond only to amplitude modulation. Such conversion systems are known and are sometimes designated hybridizers or hybridization systems in view of the fact that an applied frequency-modulated carrier signal is converted to a hybrid signal having the same frequency modulation and, in addition, amplitude modulation corresponding to the frequency modulation. For example, hybridization is effected in any network, the transmission

frequency-response characteristic of which has a finite constant slope other than zero in the pass band accommodating the frequency-modulated carrier signal and its sidebands. Thus, even after the frequency-modulated carrier signal is once hybridized, it is still necessary that subsequent carrier-signal translating networks be capable of passing a band broad enough to accommodate the frequency-modulation component sidebands otherwise severe distortion will arise in the amplitude-modulation components. On the other hand, if only the amplitude-modulation component sidebands are present, subsequent carrier-signal translating networks capable of passing a relatively narrow band may be used.

Since phase modulation differs from frequency modulation only in the magnitude of the amplitude of sidebands corresponding to a given modulation-frequency signal, it is to be understood that the term "frequency modulation" is used hereinafter to include not only frequency modulation in the rigorous sense but also phase modulation.

In addition, there exists at present the need for a converter attachment for use with conventional amplitude-modulated carrier-signal receivers by means of which the receiver may be adapted for the reception of frequency-modulated carrier signals. In such a frequency-modulation converting apparatus of this nature, as well as in frequency-modulated carrier-signal receivers, per se, it is highly desirable that the converted modulated-carrier signal be substantially entirely free of frequency-modulation components.

It is an object of the present invention, therefore, to provide a frequency-modulated carrier-signal translating system which is not subject to the aforesaid disadvantages and undesirable features of the arrangements of the prior art.

It is a more specific object of the invention to provide a frequency-modulated carrier-signal translating channel effective to alter at least one of the characteristics of a frequency-modulated carrier signal translated thereby.

It is another object of the invention to provide an improved frequency-modulated carrier-signal transmitting means.

It is another object of the invention to provide an improved frequency-modulated carrier-signal receiving means.

It is a further object of the invention to provide improved means for converting a frequency-modulated carrier signal to one having a differ-

ent type of modulation which is entirely free of frequency-modulation components.

It is an additional object of the invention to provide improved means for converting a frequency-modulated carrier signal to an amplitude-modulated carrier signal in a carrier-frequency signal-translating channel of a frequency-modulated carrier-signal receiving apparatus.

In accordance with the invention, a frequency-modulated carrier-signal translating channel comprises an input circuit adapted to have applied thereto a frequency-modulated input carrier signal and means coupled to the input circuit for selectively deriving directly from the input signal at least two separate carrier signals each having frequency-modulation components corresponding to those of the input signal. The channel also includes means for combining the derived carrier signals in substantially the same time relationship to develop an output carrier signal having modulation components dependent on the frequency-modulation components of both of the derived carrier signals and an output circuit for the output signal coupled to the combining means.

More specifically in accordance with the invention, a frequency-modulated carrier-signal translating channel particularly suitable for use in a transmitter comprises frequency-changing means for modulating a frequency-modulated carrier-signal input with a constant frequency oscillation to derive an intermediate-frequency frequency-modulated carrier signal, the frequency of which is equal to the sum of the constant frequency and the carrier frequency. The channel also includes band-pass selector means for selecting such sum-intermediate-frequency frequency-modulated carrier signal and means for modulating such selected carrier signal with the input frequency-modulated carrier signal to derive an output frequency-modulated carrier signal, the frequency of which is the sum of the sum-intermediate-carrier frequency and the input carrier frequency and the frequency deviation of which is twice that of the input signal, and band-pass selector means for selecting such output frequency-modulated carrier signal.

Further, more specifically in accordance with the invention, a frequency-modulated carrier-signal translating channel particularly suitable for use in a receiver comprises means for selectively deriving from a received frequency-modulated carrier signal at least two separate carrier signals, one having the frequency of said input signal and the other having a frequency equal to the difference of said input-signal frequency and a substantially constant frequency and effectively comprising an intermediate-frequency frequency-modulated signal. The channel also includes means for selecting and converting one of the derived signals, preferably the intermediate-frequency signal, to develop a hybrid signal carrier having amplitude-modulation components corresponding to the frequency-modulation components of said input signal, and means for combining the hybrid carrier signal with another of said derived carrier signals to develop an amplitude-modulated carrier signal having a carrier frequency equal to said substantially constant frequency and from which the frequency-modulation components are substantially balanced out.

As used herein, the term "frequency-modulated carrier signal derived from a received signal" is intended to include the received carrier

signal itself as well as an intermediate-frequency frequency-modulated wave derived therefrom.

For a better understanding of the invention, together with other and further objects thereof, reference is had to the following description taken in connection with the accompanying drawings and its scope will be pointed out in the appended claims.

Fig. 1 is a schematic circuit diagram of a frequency-modulated carrier-signal translating channel of a transmitter embodying features of the invention; Fig. 2 is a similar diagram of a complete frequency-modulated carrier-signal receiver embodying the invention; Fig. 3 is a similar diagram of a frequency-amplitude modulation converter attachment for conventional amplitude-modulated carrier-signal receivers; Fig. 4 is a similar diagram of a modification of the invention comprised in a balanced hybridizer; while Fig. 5 is a phase diagram of the voltage and current relationships in a balanced hybridizer.

Referring particularly to Fig. 1 of the drawings, there is shown a carrier-signal translating channel for a frequency-modulated carrier-signal transmitter including an input circuit having terminals 10, 10 adapted to have applied thereto a frequency-modulated carrier signal. Connected to the input terminals 10, 10 is a modulator or frequency changer 11 to which is coupled a tunable oscillator 12, there being coupled to the frequency changer 11 in cascade, in the order named, a band-pass selector 13 having a uniform transmission frequency-response characteristic over the frequency-modulation sidebands of the translated signal and a second modulator or frequency changer 14 which is coupled also to the input terminals 10, 10 by way of a band-pass translating circuit which may comprise simply conductors 15, 15. A band-pass selector 16 having a uniform transmission frequency-response characteristic over the frequency-modulation sidebands of the translated signal is coupled to the frequency changer 14 and is provided with an output circuit having terminals 17, 17. It is to be noted that the width of the frequency-modulation sidebands of the signal translated by the selector 16 is twice that of the input signal.

In considering the operation of the frequency-modulated carrier-signal translating channel of Fig. 1 which operates to double the frequency-modulation deviation of an applied frequency-modulated signal, it will be assumed that the input terminals 10, 10 are coupled to a conventional source of frequency-modulated carrier signals ω_s while the output terminals 17, 17 are coupled eventually to a conventional antenna through one or more similar channels, if desired. The frequency-modulated carrier-signal wave supplied to the frequency changer 11 is modulated by a constant-frequency oscillation voltage ω_0 from the oscillator 12 to derive an intermediate-frequency carrier signal $(\omega_s + \omega_0)$, the carrier frequency of which is the sum of the constant frequency of the oscillator 12 and the carrier frequency of the input signal and having frequency-modulation components corresponding to those of the input signal. Such intermediate-frequency signal is selected by the band-pass selector 13 and modulated in the frequency changer 14 by a frequency-modulated carrier signal ω_s derived from the received signal and translated over the band-pass circuit 15, 15 to

develop a frequency-modulated carrier-signal output ($2\omega_s + \omega_0$), the carrier frequency of which is the sum of the sum-intermediate-carrier frequency and the input carrier frequency and has frequency-modulation components dependent upon those of both of the derived carrier signals but has twice the frequency-modulation deviation of the input signal. This output wave is selected by the band-pass selector 16 for translation through the output terminals 17, 17 to an antenna for radiation. Stated in other words, the arrangement of Fig. 1 comprises means for directly deriving a plurality of separate carrier signals from the input signal, each having frequency-modulation components corresponding to those of the input signal. Specifically, the units 11, 12 and 13 comprise means for directly deriving a first carrier signal ($\omega_s + \omega_0$) and the circuit 15 comprises means for directly deriving a separate carrier signal (ω_s) from the input signal, each derived signal having modulation components corresponding to those of the input signal. The two signals so derived are thereafter combined in substantially the same time relationship in frequency changer 14 to derive the output carrier signal ($2\omega_s + \omega_0$) which has frequency-modulation components dependent upon those of each of the above-mentioned derived signals.

The fact that the frequency-modulation deviation of the signal output of frequency changer 14 of Fig. 1 selected by band-pass selector 16 is twice that of the signal input can be readily appreciated from the fact that the frequency deviations of the sum-intermediate-carrier-frequency signal output of frequency changer 11 and the signal input are in phase; that is, the carrier frequencies of these two signals swing in frequency in unison. Therefore, the sum-frequency signal output of frequency changer 14 undergoes a frequency swing twice that of the signal input. A similar result is procured in case the difference-intermediate-frequency output of frequency changer 11 is selected by selector 13 and combined with the signal input in frequency changer 14 and the difference-frequency output is selected by selector 16. In this case also the carrier-frequency deviations of the two signals combined in frequency changer 14 are in phase and the frequency deviation of the difference-frequency output is double that of the input signal. It is only necessary that similar heterodyne product signals be derived from both of the frequency changers 11 and 14, that is, both sum-frequency components or both difference-frequency components so that the frequency deviations of both signal inputs to frequency changer 14 are in phase. Either of these arrangements has the advantage that a carrier frequency may be initially modulated with a moderate frequency deviation and the deviation thereafter increased in one or more steps as described in order to produce a frequency-modulated carrier signal having any desired degree of carrier-frequency deviation.

Referring to Fig. 2 of the drawings, there is shown schematically a complete frequency-modulated carrier-signal receiver comprising coupled in cascade, in the order named, an antenna system 21, 21, a tunable radio-frequency amplifier 22 including one or more stages of amplification, a modulator or frequency changer 23 having a tunable oscillator 24 coupled thereto, a selector and hybridizer 25, a modulator or frequency changer 26 which is coupled also to

the output of radio-frequency amplifier 22 by way of a band-pass translating circuit which may comprise simply conductors 27, 27, an amplitude-modulation detector 28, an audio-frequency amplifier 29 including one or more stages of amplification, and a signal-reproducing device 30. The selector and hybridizer 25 may comprise a resistor 31 of high value, which may be comprised in whole or in part of the anode resistance of the preceding vacuum tube, a shunt inductance 32, and shunt capacitance 33, the latter being shown in dotted lines because it may be comprised in whole or in part of the inherent shunt capacitance of the circuit. The values of these circuit constants preferably are proportioned so that the frequency-response characteristic of the network has a uniform slope of substantial value over the frequency-modulation sideband range so that the input frequency-modulated carrier signal is converted into a hybrid signal.

In considering the operation of the receive of Fig. 2, a frequency-modulated carrier signal ω_s intercepted by the antenna system 21, 21 is selected and amplified in the radio-frequency amplifier 22 and this amplified frequency-modulated carrier signal is modulated in frequency changer 23 by a substantially constant frequency oscillation ω_0 from oscillator 24 to derive an intermediate-frequency frequency-modulated signal ($\omega_s - \omega_0$) having frequency-modulation components corresponding to those of the received signal. This derived signal is selected and converted to a hybrid signal including both frequency-modulation and amplitude-modulation components by the selector and hybridizer 25. This hybrid signal is applied to the frequency changer 26 and mixed therein with a frequency-modulated carrier signal ω_s , derived from the received signal through the band-pass signal-translating circuit 21, 21 and having frequency-modulation components corresponding to those of the received signal, so that the frequency-modulation components are substantially demodulated to derive an amplitude-modulated signal ω_0 that is substantially free of frequency-modulation components. In other words, the means 23, 24, 25 for selecting and supplying the signal ($\omega_s - \omega_0$) to frequency changer 26 has a transmission frequency-response characteristic which is different from that of the means 21 for selecting and supplying the signal (ω_s) to the frequency changer 26. The resulting pure amplitude-modulated constant frequency carrier signal ω_0 is detected in a conventional manner by detector 28, amplified by audio-frequency amplifier 29, and reproduced by the reproducing device 30.

A simplified explanation of the operation of the receiver of Fig. 2 may be obtained by considering a frequency-modulated carrier signal, the carrier frequency ω_s of which swings between 40 and 41 megacycles. Thus, if the local oscillator frequency ω_0 is 30 megacycles, the intermediate-carrier frequency ($\omega_s - \omega_0$) swings between 10 and 11 megacycles. The carrier-frequency output ω_0 of the frequency changer 26 is equal to the difference between the input carrier frequency and the intermediate-carrier frequency and is thus 30 megacycles regardless of the frequency swing of the input signal. However, since the hybridizer 25 has a frequency-response characteristic of uniform slope over the frequency-modulation sidebands, the 30-megacycle output varies in amplitude in accordance with the instantane-

ous deviation of the frequency-modulated carrier signal.

In its simplest form, the selector and hybridizer unit 25 comprises the circuit illustrated. The intermediate frequency is small compared to the carrier frequency of the input signal and the circuit constants of the unit 25 are so proportioned that the circuit appears as only an inductive reactance at the intermediate-carrier frequency, resonates at a frequency somewhat greater than the intermediate-carrier frequency, and appears as a negligible capacitive reactance at frequencies of the order of that of the input carrier signal and at higher frequencies. It will be apparent that the frequency-modulation components are eliminated in the output of the frequency changer 26 since the two frequency-modulation signal inputs thereto have frequency deviations which are in phase; that is, their carrier frequencies swing in unison over equal deviation ranges. Thus, the instantaneous difference frequency of these two signals is constant; that is, the frequency deviations of the two signals effectively cancel each other. Again a similar result may be procured by selecting the sum-intermediate-frequency output of frequency changer 23 heterodyning it with the input signal in frequency changer 26.

Referring to Fig. 3 of the drawings, there is shown a converter for converting a frequency-modulated carrier signal to an amplitude-modulated carrier signal substantially free of all frequency-modulation components for subsequent reception by conventional amplitude-modulated carrier-signal receivers, elements similar to those of the receiver of Fig. 2 being designated by similar reference numerals. The converter attachment of Fig. 3 differs primarily from the receiver of Fig. 2 in that the frequency changer 23 has coupled thereto a first intermediate-frequency band-pass selector 34 in place of the hybridizer 25 and the frequency changer 26 has coupled thereto a local oscillator 35. Further, the output circuit of frequency changer 26 includes a hybridizing band-pass selector network 36 which is coupled to a frequency changer 37 to the output circuit of which are coupled circuit terminals 38, 39 for connection to a conventional amplitude-modulated carrier-signal receiver.

The hybridizing band-pass selector network 36 comprises a band-pass selector consisting of a tuned primary circuit 39, 40 inductively coupled to a tuned secondary circuit 41, 42 and having a uniform transmission characteristic over the pass band corresponding to a second intermediate-frequency frequency-modulation sideband associated with the sum-intermediate-carrier frequency. The unit 36 also comprises a band-pass selector and hybridizer consisting of a tuned primary circuit 43, 44 inductively coupled to a tuned secondary circuit 45, 46 and having a transmission characteristic of uniform slope over the pass band corresponding to a third intermediate-frequency frequency-modulation sideband associated with the difference-intermediate-carrier frequency. In order to derive a hybrid signal having amplitude-modulation as well as frequency-modulation components, the signal voltage across the primary circuit 43, 44 is added to that across secondary circuit 45, 46 through blocking condenser 48 and applied to another control electrode of the frequency-changer tube 37. The output circuit of the frequency changer 37 includes a selector 47, 48 tuned to twice the frequency

of the oscillator 35 and coupled to an output including terminals 38, 39.

In considering the operation of the frequency-modulated carrier-signal converter of Fig. 3, the 5 amplified first intermediate-frequency frequency-modulated carrier signal ($\omega_s - \omega_0$) selected by the band-pass selector 34 is heterodyned in frequency changer 26 with a constant frequency oscillation to derive sum and difference second and third 10 intermediate-frequency frequency-modulated signals ($\omega_s - \omega_0 + \omega_0$) and ($\omega_s - \omega_0 - \omega_0$), respectively, having frequency-modulation components corresponding to those of the received signal, the latter of which is hybridized by selector 43, 44, 45, 15 46 to derive a hybrid carrier signal including both amplitude-modulation and frequency-modulation components. The development of such hybrid signal may be explained by the fact that, with two coupled circuits tuned to the same resonant frequency, the vector sum of the voltages 20 across the two circuits maximizes at some frequency different than their mean resonant frequency and the effective response of the selector has a steeper and more nearly uniform slope than can be procured from the response characteristic of a simple double-tuned transformer. This vector sum voltage is obtained by effectively connecting the two tuned circuits 43, 44 and 25 45, 46 in series in an input circuit of frequency 30 changer 37. The effect of such a uniformly sloping response characteristic over the frequency-modulation band is similar to that of a conventional frequency discriminator in converting frequency deviations of an applied signal to amplitude variations without, at the same time, affecting the frequency-modulation deviations. These 35 two signals are combined in the frequency changer 37 and, due to the unlike frequency-response characteristics of the selector 39, 40, 41, 42 and the selector and hybridizer 43, 44, 45, 46, the frequency changer 37 is effective to produce an amplitude-modulated carrier signal $2\omega_0$ of twice the oscillator frequency. The manner in which 40 the frequency-modulation components are eliminated from the output signal is similar to that 45 described above in connection with the system of Fig. 2.

For example, if the first intermediate-frequency frequency-modulated signal translated by 50 the band-pass selector 34 instantaneously swings from 1.9 to 2.1 megacycles and back again and the frequency of the local oscillator 35 is 270 kilocycles, the output of the frequency changer 26 includes frequency-modulated signals which 55 instantaneously swing from 2.17 to 2.37 megacycles and 1.63 to 1.83 megacycles and back again. The instantaneous frequency deviations of these two signals from their mean carrier frequencies are in the same direction and of the same magnitude. Hence, when they are selected and one is hybridized to obtain a hybrid signal having amplitude modulation as well as frequency modulation and the two are combined in the frequency changer 37, the difference-frequency signal is of constant frequency but pure amplitude-modulated. This amplitude-modulated carrier-signal output has a carrier frequency twice the oscillator frequency or, in the example given, 540 kilocycles, which is of a suitable frequency 60 to be applied to a conventional amplitude-modulated signal receiver.

The circuit of Fig. 3, as has been pointed out, is effective in converting frequency-modulated signals to amplitude-modulated signals because 75 the selector 39, 40, 41, 42, which is tuned to the

sum intermediate frequency, and the selector and hybridizer 43, 44, 45, 46, 18, which is tuned to the difference intermediate frequency, have transmission frequency-amplitude response characteristics which are unlike. However, this relation is a general one and it will be understood that, if these two signal-translating circuits have both like transmission frequency-amplitude response characteristics and like transmission frequency-phase response characteristics, the output signal at terminals 38, 38 is completely devoid of any form of modulation. On the other hand, if these two signal-translating devices have like transmission frequency-amplitude response characteristics but unlike transmission frequency-phase response characteristics, as by giving both selectors constant times of transmission with frequency but different absolute times of transmission, an input frequency-modulated carrier signal will develop an output signal at terminals 38, 38 which is solely phase-modulated.

An advantage of the circuit of Fig. 3 over that of Fig. 2 resides in the fact that both of the signals applied to the frequency changer 37 are amplified to a relatively high signal level so that the amplitude-modulated signal derived from frequency changer 37 is considerably greater in amplitude. Furthermore, the selector circuits between the two frequency changers 26, 37 contribute to the over-all selectivity of the receiver. If two tuned circuits are used in each selector, as shown, the over-all selectivity is increased by four circuits over that obtainable with the arrangement of Fig. 2. The frequency changer 23 which precedes the band-pass selector 34 is primarily effective to reduce the relatively high frequency of the received frequency-modulated signals and thus improve the selectivity obtainable by the use of a low first intermediate frequency as well as to provide amplification.

Referring particularly to Fig. 4 of the drawings, there is represented a signal-translating channel for converting a frequency-modulated carrier signal to an amplitude-modulated carrier signal by means of a "balanced hybridizer." This term may be defined as a circuit arrangement for use in a frequency-modulation to amplitude-modulation conversion system to balance out noise or residual amplitude modulation, such as transmitter hum, of a frequency-modulated carrier signal when the frequency modulation is substantially zero. The translating channel of Fig. 4 comprises an input circuit having terminals 50, 50 adapted to have applied thereto a frequency-modulated carrier signal. Coupled to the input circuit is a modulator or frequency changer 51 which is also coupled to a tunable oscillator 52. The output circuit of the frequency changer 51 includes in series a resonant circuit 53, 54 tuned to the sum-intermediate-carrier frequency thereof and a resonant circuit 55, 56 tuned to the difference-intermediate-carrier frequency thereof. A phase-shifting circuit including an inductance 57 and a resistor 58 is connected across the tuned circuit 53, 54 and the junction of inductance 57 and resistor 58 is connected to the control electrode of a frequency changer 66 by way of a conductor 59 and a parallel resonant circuit 60 tuned to the difference-intermediate-carrier frequency of the frequency changer 51. A phase-shifting circuit including a condenser 61 and a resistor 62 is also coupled across the tuned circuit 53, 54 and the junction of condenser 61 and resistor 62 is connected to the control electrode of a frequency changer 65

by way of a conductor 63 and a parallel resonant circuit 64 tuned to the difference-intermediate-carrier frequency of the frequency changer 51. The tuned circuits 60, 64 are inductively coupled in opposite phase to inductance 55. The frequency changers 65 and 66 are connected in push-pull relation to provide a common output circuit including a parallel connected condenser 67 and an inductance 68 tuned to twice the frequency of the oscillator 52. Inductively coupled to the inductance 68 is an inductance 69 for supplying a second harmonic oscillation voltage from the oscillator 52 to the output of the system by way of a selector 70 tuned to twice the oscillator frequency, a phase shifter 71, and conductors 72, 72. An output circuit including terminals 73, 73 is inductively coupled to inductance 68 by an inductance 74.

In considering the operation of the translating channel of Fig. 4, it is assumed that the input terminals 50, 50 are coupled to a frequency-modulated carrier-signal source. Such carrier signal is heterodyned with a constant frequency voltage from oscillator 52 to produce sum and difference frequency current components in the output circuit of frequency changer 51 having frequency-modulation components corresponding to those of the received signal. The explanation may be facilitated by the diagram of Fig. 5 which is a quasi-vector or phase diagram showing the relation between the instantaneous phases of the several quantities relative to the same arbitrary reference point in their respective cycles, a positive horizontal vector representing zero phase angle relative to such reference point. Furthermore, the instant at which the several quantities is represented is that at which the input carrier frequency is passing through its mean frequency. The instantaneous phases of the sum and difference frequency currents are represented by vectors I^+ and I^- in the phase diagram of Fig. 5. The difference-frequency current produces a voltage across tuned circuit 55, 56 which is represented by the vector $E^{-55,56}$ and voltages across tuned circuits 60 and 64 which are represented respectively by vectors E^{-60} and E^{-64} . The vector sum E^{-66} of voltages $E^{-55,56}$ and E^{-60} represents the total difference-frequency voltage applied to the control grid of tube 66, while the vector sum E^{-65} of voltages $E^{-55,56}$ and E^{-64} represents the total difference-frequency voltage applied to the control grid of tube 65.

When the instantaneous frequency of the frequency-modulated difference-frequency signal is other than the mean frequency, the vector relationships are altered. In general, at such frequency the voltage vector E^{-66} is lengthened while at the same instant the voltage vector E^{-65} is shortened. At another frequency on the other side of the mean frequency, vector E^{-66} is shortened and E^{-65} is lengthened. Thus, during frequency deviations of the difference-frequency signal, the voltages represented by vectors E^{-66} and E^{-65} vary in amplitude in opposite directions, that is, they represent hybrid difference-frequency voltages having their amplitude-modulation factors in opposite phase.

The sum-frequency current component I^+ develops a voltage $E^{+53,54}$ across tuned circuit 53, 54, a voltage E^{+65} across resistor 62 which is a part of the phase-shifting circuit 61, 62, and a voltage E^{+66} across resistor 58 which is a part of the phase-shifting circuit 57, 58. E^{+66} and E^{+65} represent the net sum-frequency voltages applied to the control grids of tubes 66 and 65, respectively.

The sum-frequency voltage vectors, as shown in Fig. 5, represent conditions when the frequency-modulated sum-frequency carrier signal is passing through its mean frequency. By appropriately damping tuned circuit 53, 54, the sum-frequency voltage vectors remain constant in amplitude over a frequency band including the maximum frequency deviations of the frequency-modulated sum-frequency carrier signal.

The application of voltages E^{-ss} and E^{+ss} to tube 66 produces by heterodyne detection a plate current component I_{ss} of twice oscillator frequency which is amplitude-modulated and substantially free of frequency-modulation components. Similarly the application of voltages E^{-ss} and E^{+ss} to tube 65 produces a plate current component I_{ss} which is also amplitude-modulated and substantially free of frequency-modulation components. When the circuit is so proportioned that the phase angle θ^- between the sum-frequency current I^+ and the voltage E^{+ss} is equal to the phase angle θ^+ between the difference-frequency current and the voltage E^{-ss} at zero frequency modulation of the sum-frequency and difference-frequency signals and the scalar product of E^{-ss} and E^{+ss} is equal to the scalar product of E^{-ss} and E^{+ss} , the currents I_{ss} and I_{ss} are equal and in phase. Hence, by reason of the balanced output circuit 67, 68 no energy is transferred to coupling inductance 74 when the input signal applied to terminals 50, 50 is not frequency-modulated. Similarly, energy is not transferred to inductance 74 when the input signal is solely amplitude-modulated, since the amplitude modulation is in phase in the two currents I_{ss} and I_{ss} . However, if frequency modulation appears on the input carrier signal, the balanced hybridizer causes the currents I_{ss} and I_{ss} to be amplitude-modulated in opposite phase. The signal that is produced at terminals 73, 73 is then an amplitude-modulated signal without a carrier component, the amplitude modulation of which is in correspondence with the frequency modulation of the input signal. A noise free and unmodulated carrier may be re-supplied by selecting the second harmonic of oscillator 52 by selector 70, correcting its phase appropriately by phase-shifting circuit 71 and coupling it to the output through inductance 69, tuned circuit 67, 68, and inductance 74 to enable the resultant amplitude-modulated carrier signal to be detected in a conventional manner.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A frequency-modulated carrier-signal translating channel comprising, an input circuit adapted to have applied thereto a frequency-modulated input carrier signal, means coupled to said input circuit for selectively deriving directly from said input signal at least two separate carrier signals each having frequency-modulation components corresponding to those of said input signal, means for combining said derived carrier signals in substantially the same time relationship to develop an output carrier signal having modulation components dependent upon the frequency-modulation components of both of said

derived carrier signals, and an output circuit for said output signal coupled to said last-named means.

2. A frequency-modulated carrier-signal translating channel comprising, an input circuit adapted to have applied thereto a frequency-modulated input carrier signal, means coupled to said input circuit for selectively deriving directly from said input signal at least two separate carrier signals of different frequencies each having frequency-modulation components corresponding to those of said input signal, means for combining said derived carrier signals to develop an output carrier signal having modulation components dependent upon the frequency-modulation components of both of said derived carrier signals, and an output circuit for said output signal coupled to said last-named means.

3. A frequency-modulated carrier-signal translating channel comprising, an input circuit adapted to have applied thereto a frequency-modulated input carrier signal, means coupled to said input circuit for selectively deriving from said input signal two separate carrier signals one having the frequency of said input signal and the other having a frequency equal to that of a heterodyne product of said input signal and a substantially constant frequency oscillation and each having frequency-modulation components corresponding to those of said input signal, means for combining said derived carrier signals to develop an output carrier signal having modulation components dependent upon the frequency-modulation components of both of said derived carrier signals, and an output circuit for said output signal coupled to said last-named means.

4. A frequency-modulated carrier-signal translating channel comprising, an input circuit adapted to have applied thereto a frequency-modulated input carrier signal, means coupled to said input circuit for selectively deriving from said input signal two separate carrier signals one having the frequency of said input signal and the other having a frequency equal to that of a heterodyne product of said input signal and a substantially constant frequency oscillation and each having frequency-modulated components corresponding to those of said input signal, means for combining said derived carrier signals to develop a frequency-modulated output signal having a frequency equal to that of a heterodyne product of the frequencies of said derived carrier signals and an increased frequency-modulation deviation, and an output circuit for said output signal coupled to said last-named means.

5. A frequency-modulated carrier-signal translating channel comprising, an input circuit adapted to have applied thereto a frequency-modulated input carrier signal, frequency-changing means coupled to said input circuit for modulating said input signal with a constant frequency oscillation to derive an intermediate-frequency frequency-modulated carrier signal the frequency of which is equal to that of a heterodyne product of the constant frequency oscillation and the input signal carrier frequency, band-pass selector means for selecting said intermediate-frequency signal, frequency-changing means for modulating said intermediate-frequency signal with the input signal to derive an output frequency-modulated carrier signal the frequency of which is equal to that of a similar heterodyne product of said intermediate-frequency signal and the input signal and the frequency deviation of which is

substantially greater than that of said input signal, and band-pass selector means for selecting said output frequency-modulated carrier signal.

6. A frequency-modulated carrier-signal translating channel comprising, an input circuit adapted to have applied thereto a frequency-modulated input carrier signal, means coupled to said input circuit for selectively deriving from said input signal a plurality of separate carrier signals each having frequency-modulation components corresponding to those of said input signal, means for selecting at least two of said derived carrier signals comprising band-pass translating circuits having different transmission frequency-response characteristics over their respective pass bands, means for combining said last-named carrier signals to develop an output signal which depends upon the frequency-modulation components of both of said derived carrier signals, and an output circuit for said output signal coupled to said last-named means.

7. A frequency-modulated carrier signal translating channel comprising, an input circuit adapted to have applied thereto a frequency-modulated input carrier signal, means coupled to said input circuit for selectively deriving from said input signal a plurality of separate carrier signals each having frequency-modulation components corresponding to those of said input signal, means for selecting at least two of said derived carrier signals comprising selectors having different transmission frequency-phase response characteristics, means for combining said last-named carrier signals to develop a phase-modulated output signal from which the frequency-modulation components are substantially balanced out, and an output circuit for said output signal coupled to said last-named means.

8. A frequency-modulated carrier-signal translating channel comprising an input circuit adapted to have applied thereto a frequency-modulated input carrier signal, means coupled to said input circuit for selectively deriving from said input signal a plurality of separate carrier signals each having frequency-modulation components corresponding to those of said input signal, means for selecting at least two of said derived carrier signals comprising band-pass translating circuits having different transmission frequency-amplitude response characteristics, means for combining said last-named carrier signals to develop an amplitude-modulated output signal from which the frequency-modulation components are substantially balanced out, and an output circuit for said output signal coupled to said last-named means.

9. A frequency-modulated carrier-signal translating channel comprising, an input circuit adapted to have applied thereto a frequency-modulated input carrier signal, means coupled to said input circuit for selectively deriving from said input signal at least two separate carrier signals one having the frequency of said input signal and the other having a frequency equal to the difference of said input signal frequency and a substantially constant frequency and each having frequency-modulation components corresponding to those of said input signal, means for selecting and converting at least one of said derived carrier signals to a hybrid carrier signal including amplitude-modulation components corresponding to the frequency-modulation components of said input signal, means for combining said hybrid carrier signal with another of

said derived carrier signals to develop an amplitude-modulated output signal having a carrier frequency equal to said substantially constant frequency and from which the frequency-modulation components are substantially balanced out, and an output circuit for said output signal coupled to said last-named means.

10. A frequency-modulated carrier-signal translating channel comprising, an input circuit adapted to have applied thereto a frequency-modulated input carrier signal, means coupled to said input circuit for selectively deriving from said input signal at least two separate carrier signals one having a frequency equal to the sum of said input signal frequency and a substantially constant frequency and the other having a frequency equal to the difference of said input signal frequency and said substantially constant frequency and each having frequency-modulation components corresponding to those of said input signal, means for selecting and converting at least one of said derived carrier signals to a hybrid carrier signal including amplitude-modulation components corresponding to the frequency-modulation components of said input signal, means for combining said hybrid carrier signal with the other of said derived carrier signals to develop an amplitude-modulated output signal having a carrier frequency equal to twice said substantially constant frequency and from which the frequency-modulation components are substantially balanced out, and an output circuit for said output signal coupled to said last-named means.

11. A frequency-modulated carrier-signal translating channel comprising, an input circuit adapted to have applied thereto a frequency-modulated input carrier signal having undesired modulation components which may include signal and noise amplitude-modulation components, means coupled to said input circuit for selectively deriving a plurality of separate carrier signals each having frequency-modulation components and said undesired modulation components corresponding to those of said input signal, means for selecting at least two of said derived carrier signals comprising band-pass translating circuits having different transmission frequency-response characteristics, means for combining said derived carrier signals to develop an output signal from which the frequency-modulation components and said undesired modulation components are substantially balanced out and which contains amplitude-modulation components corresponding only to the frequency-modulation components of said input signal, and an output circuit for said output signal coupled to said last-named means.

12. A frequency-modulated carrier-signal translating channel comprising, an input circuit adapted to have applied thereto a frequency-modulated input carrier signal having undesired modulation components which may include signal and noise amplitude-modulation components, means coupled to said input circuit for selectively deriving a plurality of separate carrier signals each having frequency-modulation components and said undesired modulation components corresponding to those of said input signal, means for selecting at least two of said derived carrier signals comprising selectors having different transmission frequency-amplitude response characteristics, means for combining said last-named carrier signals to develop an output signal from which the frequency-modulation components

and said undesired modulation components and the carrier are substantially balanced out and which contains amplitude-modulation components corresponding only to the frequency-modulation components of said input signal, an output circuit for said output signal coupled to said last-named means, and means coupled to said output circuit for supplying a carrier for said amplitude-modulation components.

13. A frequency - modulated carrier - signal translating channel comprising, an input circuit adapted to have applied thereto a frequency-modulated input carrier signal having undesired modulation components which may include signal and noise amplitude-modulation components, means including a constant frequency oscillator coupled to said input circuit for selectively deriving a plurality of separate carrier signals each having frequency-modulation components and said undesired modulation components corresponding to those of said input signal,

means for selecting at least two of said derived carrier signals comprising selectors having different transmission frequency-amplitude response characteristics, means for combining said last-named carrier signals to develop an output signal from which the frequency-modulation components and said undesired modulation components and the carrier are substantially balanced out and which contains amplitude-modulation components corresponding only to the frequency-modulation components of said input signal, an output circuit for said output signal coupled to said last-named means, and means coupled to said output circuit for supplying a carrier for said amplitude-modulation components including means coupled to said oscillator for deriving a carrier the frequency of which is a harmonic of the constant frequency of said oscillator.
